G. B. KOHLER,
GUIDE FOR PIVOTED DOORS,
APPLICATION FILED OCT. 26, 1914.

Patented Dec. 7, 1915.
2 SHEETS—SHEET 2.

UNITED STATES PATENT OFFICE.

GEORGE B. KOHLER, OF PHILADELPHIA, PENNSYLVANIA, ASSIGNOR TO THE J. G. BRILL COMPANY, OF PHILADELPHIA, PENNSYLVANIA, A CORPORATION OF PENNSYLVANIA.

GUIDE FOR PIVOTED DOORS.

1,163,418.

Specification of Letters Patent. Patented Dec. 7, 1915.

Application filed October 26, 1914. Serial No. 868,765.

To all whom it may concern:

Be it known that I, GEORGE B. KOHLER, a citizen of the United States, residing in Philadelphia, Pennsylvania, have invented 5 certain Improvements in Guides for Pivoted Doors, of which the following is a specification.

This invention relates to certain improvements in means for guiding the outer section 10 of a multiple-section pivoted door, where one section folds against another section.

The invention is particularly adapted for use in railway passenger cars where it is desired to so locate the mechanism that when 15 the door is open it will extend partly over the platform.

Heretofore, it has been necessary to provide a cam-shaped or curved guide rail for the outer door section when the pivot for 20 the door was inside the plane of the doors when the doors were closed, consequently, the roller would not work freely in the guide and in many instances it would bind, preventing the full opening of the doors.

25 The object of my invention is to so improve the construction that a straight rail can be used, the rollers traveling freely along the guide rail from the open to the closed position.

30 In the accompanying drawings:—Figure 1, is a view, in elevation, of the upper portion of a car door and frame, showing the door in the closed position and illustrating my invention; Fig. 2, is a plan view of the 35 door and frame, showing the door in the closed position; Fig. 3, is a view, similar to Fig. 2, with the door in the open position; Fig. 4, is a sectional view on the line $a-a$, Fig. 1; Fig. 5, is a perspective view of the 40 heading of the door, showing the straight guide rails; Fig. 6, is a view of the upper portion of the door, showing the rollers which are adapted to the guide rails; Fig. 45 7, is a detached perspective view of the bracket and the roller guide detached; Fig. 8, is a sectional view of the bracket and roller guide, showing the upper end of the door in dotted lines; and Figs. 9 and 10, are views of modifications of the invention.

50 Referring to the drawings, 1 is the frame of the door.

2 is the guide rail, which is secured to the head portion of the frame 1, as illustrated in Fig. 5, and 3 is the other rail separated

from the rail 2 a sufficient distance to allow 55 the guide rollers to travel in the space. Both of these rails are straight and extend the full width of the door opening.

4 is the inner section of the door and 5 is the outer section, being pivoted to the inner 60 section by any suitable type of hinges 6, so that the sections of the door, when open, will assume the position illustrated in Fig. 3.

7 is the upper pivot bracket for the door, having a pivot pin 8 which enters a socket 65 9 in a bracket 10, which is secured to the inner section 4 of the door. It will be noticed that both brackets are extended so that the pivot point is some distance from the door frame and from the inner surface of the 70 door, and that the pivot bracket 10 of the door is located some distance from the inner edge of the door. By arranging the pivots in this manner, the door swings in so that, when it is full open, it is in the position 75 illustrated in Fig. 3, extending partly over the door frame and partly over the platform. Consequently, the door does not project beyond the side frame of the car.

Secured to the outer door section 5, preferably some distance from the pivot point, as indicated in Fig. 1, is a bracket 11; the door being recessed at the upper edge, as indicated in Figs. 1 and 4, to receive the bracket, and pivoted at 12 to the projecting 85 portion of the bracket is a guide 13 having two pins 14 on which are mounted the rollers 15. These rollers travel between the two rails 2 and 3 and guide the outer section of the door as the door is opened and closed. 90 The pivot 12 projects beyond the outer face of the door, as illustrated in Figs. 4 and 6, so that, when the door is moved, the rollers control the guide 13, keeping it from turning but allowing it to slide freely between the 95 rails while the bracket and the door section 5 turn on the pivot 12 so that, when the door is in the closed position, the section 5 will assume the position clearly shown in Fig. 3. Thus curved rails are dispensed with and a construction is provided which will allow the door to open and close with the least amount of friction.

Any suitable mechanism may be used for opening and closing the doors, or the doors 105 may be opened or closed by hand, if desired.

In Fig. 9, I have shown the invention applied to a single rail 2^a, in which instance the

rollers 15^a are located on either side of the rail, as shown; the guide 13^a being made as illustrated in Fig. 6.

In Fig. 10, I have substituted a flange 15^b on the edge of the guide 13^b, and this flange extends in between the two guide rails 2 and 3, which may be arranged close together in this instance. This device, however, will not work so freely as that illustrated in Fig. 6, but may be used where a narrow construction is desired.

I claim:

1. The combination of a frame having a doorway; a door made in sections, one section being hinged to the other, the inner section being pivotally connected to the frame inside of the plane of the door when the door is closed; a straight rail on the frame; a bracket on the outer section of the door; and a guide pivoted to the bracket, the pivot being some distance from the side of the door, said guide having a portion engaging the rail so that the outer section of the door will move freely to its open or closed position.
2. The combination of a door frame; a multiple section door, the inner section of the door being hinged to the frame some distance back of the door when the door is closed, the outer section being hinged to the inner section so that, when the door is in the open position, the outer section will fold against the inner section; a horizontal

straight guide rail; a bracket on the outer section of the door; a guide pivotally connected to the bracket, the pivot being on the outside of the door, said guide engaging the rail so that, when the door is opened or closed, the outer section will be guided by the rail and will move freely to the open or closed position.

3. The combination in a door frame, of a two-section door, the two sections being pivotally connected by a hinge at the inside of the door, the inner section being pivoted to the frame some distance from the inside of the frame of the door when the doors are closed; two rails on the heading of the door frame, said rails being straight and spaced apart; a bracket on the upper edge of the outer section of the door; and a guide pivoted to the bracket, the pivot being on the outer side of the door, said guide having two rollers projecting into the space between the rails so that the guide, when the door is opened or closed, travels in the space between the rails, the door swinging on the pivot connecting the bracket with the guide.

In testimony whereof, I have signed my name to this specification, in the presence of two subscribing witnesses.

GEORGE B. KOHLER.
